UNITED STATES PATENT OFFICE.

WILLIAM A. E. HENRICI, OF SYRACUSE, NEW YORK, ASSIGNOR, BY DIRECT AND MESNE ASSIGNMENTS, OF ONE-HALF TO EDWIN E. SIBLEY, OF CHELSEA, MASSACHUSETTS.

IRONING-BOARD.

SPECIFICATION forming part of Letters Patent No. 426,014, dated April 22, 1890.

Application filed December 5, 1888. Serial No. 292,737. (No model.)

To all whom it may concern:

Be it known that I, WILLIAM A. E. HENRICI, of Syracuse, in the county of Onondaga, in the State of New York, have invented new and useful Improvements in Ironing-Boards, of which the following, taken in connection with the accompanying drawings, is a full, clear, and exact description.

This invention relates to improvements in ironing-boards, whereby there is produced a board whereon shirts may be quickly secured in such manner as to allow them to be run through the ironing-rolls without danger of tearing the shirts or disarranging them on the board. This is accomplished in such manner as to leave the neckband of the shirt unaffected by the ironing-rolls, so that the same may be afterward smoothly ironed and finished in a uniform style, so that all the shirts ironed on my improved board may be as nearly uniform in appearance as possible, this being particularly desirable in shirt-factories, where new goods are made in large quantities; and my invention consists in contain peculiarities of construction, as will be hereinafter more fully set forth in the specification and specifically pointed out in the claims.

In the annexed drawings, Figure 1 is a plan view of my new ironing-board with a shirt secured thereon in position ready to be ironed. Fig. 2 is a plan view having part of the covering thereof removed to show the different layers of padding, and having part of the revoluble block broken off to show the inclosed spring to better illustrate the details of construction. Fig. 3 is a side view showing the clamping device for the upper end of the shirt thrown back. Fig. 4 is a plan view of the neckband-retaining device in its closed position. Fig. 5 is an end view of the same in its open position. Fig. 6 is an inverted plan view of a portion of the body of my improved board, showing the rod D hinged to said board. Fig. 7 is a face view of one of the retaining-blocks, showing the serrations thereon. Fig. 8 is a sectional view of a part of the clamping-roll and its spring and shaft.

In the construction of ironing-boards it is desirable that the board and its appurte-
nances be so arranged that the shirt may be

quickly and firmly secured thereon, and at the same time may have a smooth yielding base upon which to rest, so as to hold the bosom smooth, while allowing it to yield slightly to the ironing-rolls as it passes through, so that 55 the force of the same will in a measure be overcome.

In constructing my device a wooden base A is first provided of the desired form, and upon this is cemented a sheet of rubber B, 60 which is at least as large as the bosom of the shirt to be ironed. Over this is stretched several thicknesses of muslin, and over all a sheet of linen C. This cloth covering is held in place by pins projecting laterally from the 65 sides of the wooden base. After the cloth covering is in position the steel strips b b are screwed down, so that the pins a a will be forced through all the thicknesses of cloth and into the holes a' a' in said strips, thus 70 preventing any accidental escape of said cloth covering from said pins.

To the under side of the board, Fig. 6, is hinged the rod D, at the end of which is secured the central part of an arc-shaped spring E, 75 to which are secured the blocks F F, said rod D resting in the longitudinal groove i on the under side of the board when the blocks are in their closed position on the board. At the opposite end of the board, on a fixed shaft G', 80 is mounted the revoluble block or roll G, preferably of wood, and recessed longitudinally for the reception of a spring H, coiled on said shaft and fitting tightly between the block and shaft. The block is free to revolve in the direction shown by the arrow, but is held against movement in the opposite direction by the free end of the spring acting as an elastic detent on the block. The outer end of the spring is secured to the block and the inner end is 85 free. When the block is pressed in the direction of the coil, the spring is wound more tightly about the shaft, clutching the same and locking the block thereto. Movement of the block in the opposite direction unwinds 90 the coil and loosens the spring on the shaft, allowing the block to turn freely.

The top end of the board is provided with the opening O of the form it is designed to shape the neckband, and is provided with 95 100

the brace J, which firmly braces the end of the board, said brace being provided with the stud j, which is hereinafter explained.

In practice my board is used as follows: The shirt to be ironed is slipped over the body portion of the board, and the rod D, with its spring and blocks, is closed over the upper end of the shirt, bearing thereon at the yokes, so that it is held in the same position as on the person of the wearer. This is more securely effected by reason of the spring E pressing the blocks provided with serrations M on their contact-faces against corresponding serrations N on the outer faces of the brace J at the point of contact. The lower end of the skirt of the shirt is then drawn down back of the board and the upper button-holes of the neckband are slipped over the stud j, so that the shirt is held in substantially the position in which it is to be worn on the person. After the shirt is thus secured at the upper end the skirt is turned over around the roller G and is stretched as tightly as possible without tearing by turning said block with the hand in the direction indicated by the arrow. The neckband is then turned down into the opening O, formed to fit it, and the spring-retaining device K is inserted in the opening O of the board, 30 with the stud j projecting through the U-shaped opening e in said spring K, after which the lever L is pressed down in the V-shaped opening in said spring K and forces the same outward, pressing it against the neckband of the shirt and holding said neckband in place in said opening O, the top edge of said spring being substantially on a level with the plane of the shirt-bosom, so as not to interfere with the operation of the ironing-rolls under which it is to be passed. It will be observed that when the shirt has been properly placed in position on my improved board it is secured against any accidental displacement, and the bosom may be ironed without in any manner affecting the neckband. More than this, the entire bosom may be ironed at one operation by the rolls, and as the opening O in the bosom-board is of the contour it is intended to have the neckband the band may be afterward finished without again dampening. As the neckband is buttoned in the opening O and held therein by the spring K, it is impossible for it to slip out or come in contact with the ironing-rolls until released by the operator.

The roll G, provided with the spring H, may be freely revolved in the direction required to stretch the shirt over the board to tighten the bosom, but it is held against re-60 turning to allow the shirt to escape from its proper position until it is ironed, when it may be released by simply drawing on the free end of the shirt to withdraw the folds from under the roll.

When it is desired to renew the cloth covering of the board, the strips b b are unscrewed, leaving the pins in an exposed position, so

that the cloth may be drawn off and a new covering substituted. To insure said pins against accidental displacement or removal, they are secured by passing them through the metal strips a² a², through which they are projected. The roll G is preferably of wood and is journaled on the shaft G', which passes longitudinally through it. 75

Having described my invention, what I claim as new, and desire to secure by Letters Patent of the United States, is—

1. In an ironing-board for shirts, a neck-band opening provided with a stud, a spring-retaining device for holding the band, a clamp for securing the yoke, and a device for stretching the bosom on the board, all combined substantially as shown. 80

2. An ironing-board for shirts, provided with a clamp for the yokes thereof, consisting of a rod hinged at one end centrally to the under side of the board, and an arc-shaped spring centrally secured to the other end of the rod, and having its ends free and each 90 provided with a retaining-block acting to clamp the yokes of the shirt against the upper end of the board, substantially as described.

3. An ironing-board for shirts, provided at 95 one end with an opening for the neckband, a stud projecting into said opening, and a retaining-spring adapted to conform to the contour of said opening to hold the band therein, in combination with a revoluble 100 tightening-block at the other end to draw the shirt over the board, and kept in position by a spring-detent, substantially as described.

4. An ironing-board for shirts, provided with a tightening device consisting of a block or roll mounted on a fixed shaft and longitudinally recessed, combined with a spring coiled on said shaft, allowing free rotation of the block in one direction and acting as an elastic detent against motion in an opposite direction, substantially as described. 105

5. An ironing-board for shirts, provided at one end with an opening and a curved spring-clamp therein for the neckband, and with yoke-clamping blocks on the free ends of an 110 arc-shaped spring centrally secured to a rod which is centrally hinged to the under side of the board, said board having at its other end on a fixed shaft a recessed revoluble block, and a spring coiled on the shaft and fitting tightly 115 in said recess between the block and shaft, all combined, substantially as set forth, to securely clamp the shirt to the board at all desirable points. 120

6. An ironing-board for shirts, provided at 125 one end with spring-clamps for the yoke, a recess for the neckband, and curved spring-clamp fitting therein, and having at its other end a tightening-block mounted on a fixed shaft and recessed for a spring coiled on said 130 shaft and acting as an elastic detent against motion of the block in one direction, while allowing it to rotate freely in the opposite direction, all substantially as described.

7. In an ironing-board, the combination of a wooden base, a rubber cushion secured thereto, and a cloth covering over all, said cloth covering being removably attached to the base by means of strips of metal pressing said cloth onto the pins projecting laterally from the base, all constructed and arranged substantially as specified and shown.

8. As a new article of manufacture, a neck-band-retaining device consisting wholly of a curved spring, and a pivoted arm having an enlargement acting directly on the two adjacent parts of said spring to distend it, substantially as described.

9. As a new article of manufacture, a neck-band-retaining device consisting of a spring substantially circular in shape exteriorly, with its ends bent into the interior of the circle, and an arm pivoted between the ends of said spring and provided with an enlarged free end for

distending the said spring, substantially as shown and set forth.

10. As a new article of manufacture, a neck-band-retaining device consisting of a spring provided with an excision to accommodate the shirt-stud, and an arm pivoted between the ends of said spring and provided with an enlarged free end for distending said spring, constructed substantially as described and shown.

In testimony whereof I have hereunto signed my name, in the presence of two attesting witnesses, at Syracuse, in the county of Onondaga, in the State of New York, this 3d day of December, 1888.
